J. A. MARTIN, OF STRASBURG, PENNSYLVANIA.

Letters Patent No. 85,839, dated January 12, 1869.

IMPROVEMENT IN GATE-LATCHES.

The Schedule referred to in these Letters Patent and making part of the same.

To all whom it may concern:

Be it known that I, J. A. MARTIN, of Strasburg, in the county of Lancaster, and State of Pennsylvania, have invented a new and improved Gate-Latch; and I do hereby declare that the following is a full, clear, and exact description thereof, which will enable others skilled in the art to make and use the same, reference being had to the accompanying drawings, forming a part of this specification, in which—

Figure 1 is a front view of a gate provided with my improved latch.

Figure 2 is a detail view of the latch-mechanism, showing its arrangement in a recess in the post.

Similar letters of reference indicate corresponding parts.

The object of this invention is to provide a simple and effective gate-latch, which is not liable to get out of repair, and which supports part of the weight of the gate.

It consists in the peculiar construction and operation of the same, as will be hereinafter more fully described.

The plates *a* and *b* are arranged within a suitable recess in the gate-post *A*, the plate *a* being pivoted therein by a bolt, *f*, on which the said plate vibrates, when actuated to do so by pressing in on either of its extensions, *c c*.

The plate *b* being pivoted to the plate *a*, by a bolt or rivet, *g*, and a stud-pin, *e*, being arranged in the side

of the recess, as shown, when either of the extensions *c* is pressed upon, the similar extension on the plate *b* will encounter the stud-pin *e*, and the said plate be raised thereby, so that the projection *d*, affixed to the gate, will be permitted to escape and the gate opened.

The weight of the gate upon the plate *a* will serve to keep the latter in its horizontal position, and, when on it, the plate *b*, removed from contact with the stud-pin, will fall, and enclose the projection in the rectangular space formed by the notches in the two plates.

h h are holes in the plates *a* and *b*, through which to pass the ring of a padlock, when the gate is to be locked.

The upper surfaces of the extensions *c c* are curved downward slightly, so that the projection *d* on the gate will slide over one of them into the notches of the plates when the gate is swung to and from either direction.

Having thus described my invention,

What I claim as new, and desire to secure by Letters Patent, is—

The gate-latch, constructed, as described, of the upper and lower notched plates *a b*, pivoted together at *g*, and to the gate-post at *f*, and arranged to operate in connection with the pin *e*, in the manner described for the purpose specified.

J. A. MARTIN.
